UNITED STATES PATENT OFFICE.

EUGENE O. MAN AND CLAUDE C. MCFATE, OF DENVER, COLORADO.

REGISTERING SEAL FOR CAR AND OTHER DOORS.

Application filed March 21, 1925. Serial No. 17,379.

This invention relates to seals for car and other door locks, and has for one of its objects the provision of a novel device of this character which shall include a register 5 adapted to be actuated by and during each application of the seal, whereby to provide for each application of the seal a number by which it may be determined whether the seal has been removed and replaced by an 10 unauthorized person.

A further object of the invention is the provision of a seal of the character stated which may be easily and quickly applied or removed, and which shall be simple and 15 durable and inexpensive of manufacture.

With the above and other objects in view, the invention consists of the construction, combination and arrangement of parts hereinafter fully described and claimed, and illustrated in the accompanying drawings, 20 wherein:

Figure 1 is an elevational view illustrating the application of the seal,

Figure 2 is a view in front elevation on 25 an enlarged scale of the seal,

Figure 3 is a view in side elevation on an enlarged scale of the seal,

Figure 4 is a sectional view taken on the 30 plane indicated by the line 4-4 of Figure 2,

Figure 5 is a sectional view taken on the plane indicated by the line 5-5 of Figure 4;

Figure 6 is a sectional view taken on the plane indicated by the line 6-6 of Figure 2,

Figure 7 is a sectional view taken on the 35 plane indicated by the line 7-7 of Figure 6,

Figure 8 is a view similar to Figure 7 showing one of the pinions in position to advance one of the numbered wheels, and

Figure 9 is a sectional view taken on the 40 plane indicated by the line 9-9 of Figure 4.

Corresponding and like parts are referred to in the following description, and designated in the several views of the accompanying drawings by similar reference characters.

In the drawings 1 designates a casing which is provided in its front wall with a sight opening 2 closed by a glass panel 3 and which is provided with a finger 4 extending upwardly from the rear wall thereof.

The register comprises wheels 5, 6, 7 and 50 8 each numbered from 0 to 9 and loosely mounted upon a stationary shaft 9. The wheels 5-8 are so arranged within the casing 1 that a single number of each is visible through the opening 2. Each of the wheels

5-8 is provided at one side of a disk 10 which is smaller in diameter than the wheel and which is provided with a radial notch 11. Disks 12 are secured to the disks 10, 60 and each of the former is provided with a pair of gear teeth 13. The gear teeth 13 are located at opposite sides of the notches 11. The wheels 6-8 have secured to their opposite sides spur pinions 14, and the wheel 65 5 has secured to the similar side thereof a ratchet disk 15. Pinions 16, 17 and 18 are loosely mounted upon a stationary shaft 19 and provided with alternately arranged wide teeth 20 and narrow teeth 21, the wide teeth 70 20 contacting with the peripheries of the disks 10 and the narrow teeth 21 engaging the teeth of the gears 14. A pawl 22 yieldingly held by a spring 23 in engagement 75 with the teeth of the ratchet wheel 15, prevents casual movement of the wheel 5, and the engagement of the wide teeth 20 with the peripheries of the disks 10 of the wheels 5-8 prevents the wheels 6, 7 and 8 from 80 having casual movement. A step by step movement is imparted to the wheel 5 through the medium of a disk 24 which is loosely mounted upon the shaft 9 and which is provided with a pawl 25 yieldingly held in contact with the teeth of the ratchet wheel 15 85 by a spring 26. When the disk 24 is rocked in one direction, the wheel 5 is advanced one number, and when the wheel 5 has been completely rotated it will advance the wheel 6 one step due to the connection established 90 between these wheels by the pinion 16 and the notch 11 and gear teeth 13 of the wheel 5. The wheel 6 will similarly operate the wheel 7 and the latter will similarly operate the wheel 8. When the disk 24 is released 95 it is returned to normal position by means of a spring 27. The register may be provided with as many numbered wheels as found desirable or necessary.

A bar 28 is slidably supported upon the 100 front side of the finger 4 by short flanges 29 extending inwardly from the opposite vertical edges of the finger and overlapping the bar. The lower end of the bar 28 extends into the casing 1, and is provided 105 with a transversely extending elongated slot 30 for the reception of a pin 31 carried by the arm 32 of an elbow lever 33. The lever 33 is pivoted as at 34 to the inner side of the rear wall of the casing 1, and 110 its arm 35 lies in the path of a lug 36 carried by the disk 24. The bar 28 is nor-

mally supported in elevated position, and the arm 35 of the lever 33 is normally retained in spaced relation to the lug 36, by a spring 37. To limit the movement 5 of the bar 28 and the lever 33 under the influence of the spring 37, a stop 38 is secured to the rear wall of the casing 1 in the path of the arm 35. Whenever the bar 28 is moved downwardly or inwardly, it rocks the 10 lever 33 in the direction to carry the arm 35 thereof into contact with the lug 36 and rock the disk 24 on the shaft 9 against the tension of the spring 27. This movement of the disk 24 imparts a step by step motion 15 to the numbered wheel 5. When the bar 28 is released the spring 37 returns it and the lever 33 to their normal positions and the spring 27 returns the disk 24 to its normal position. The bar 28 is moved downwardly and inwardly on each application of 20 the seal, and due thereto the register will be actuated on each application of the seal in such a manner as to provide a number by which it may be determined whether the 25 seal has been removed and replaced by an unauthorized person. In applying the seal, the finger 4 is adapted to be inserted through the slot 39 of the pin or bolt 40 of a door or other lock. During the application of 30 the seal the flanged upper end 41 of the bar 28 contacts with the pin or bolt 40, and as the result the bar is moved downwardly and advances the register one number.

To retain the tongue 4 applied to the pin 35 or bolt 40 a latch 42 is pivotally connected to the front side of the tongue 4 by a bolt 43 passing through the latch and through ears 44 carried by the tongue. The latch is 40 of channel formation, including a front side 45 disposed opposite the front side of the tongue 4 and lateral sides 46 embracing the lateral edges of the tongue 4. The latch 42 is pivoted at its lower end to permit its upper end to be swung forwardly and rearwardly with respect to the tongue 4 during 45 the application or removal of the seal. A coil spring 47 which surrounds the pivot pin 43 and the ends of which engage the lower edges of the lateral sides 46 of the 50 latch 42, normally holds the latch in closed position. The movement of the latch 42 in the direction of the tongue 4 under the influence of the spring 47 is limited by the forward end of the flange 41 of the bar 28. 55 The upper edges of the lateral sides 46 of the latch 42 are inclined downwardly and rearwardly as at 48 to permit the latch to be swung forwardly with respect to the tongue 4 by the bolt or pin 40 during the 60 application of the seal. When the seal is applied, the bolt or pin 40 occupies recesses 49 in the lateral sides 46 of the latch 42, and as soon as the pin or bolt is in these recesses 65 the latch 42 is returned to closed position by the spring 47. It will thus be seen that

the seal cannot become accidentally detached from the bolt or pin 40, and that the latter holds the bar 28 depressed until the removal of the seal. When the bar 28 is depressed a lug 50 carried by the front side 70 thereof engages the lower angular end 51 of a trigger 52. The trigger 52 is pivoted at its lower end upon a bolt 53 carried by the lugs 44 and is provided with a vertical slot 55 which receives a bolt 56 carried by the 75 lateral sides 46 of the latch 42. When the lug 50 is in contact with the angular end 51 of the trigger 52, the latch 42 is held against casual forward movement. Although the seal is held against accidental 80 removal from the bolt or pin 40, by the parts 47, 50 and 52, it may be manually removed with comparatively little effort, and when removed the parts 28, 33 and 24 are returned to their normal positions by the 85 springs 37 and 27.

From the foregoing description, taken in connection with the accompanying drawings, it should be apparent that when the seal is applied the register will be actuated 90 to present a number at the opening 2 by which it may be determined whether the seal has been removed and reapplied by an unauthorized person, and that since the seal cannot be removed and reapplied without 95 changing the number it is impossible for an unauthorized person to remove and reapply the seal without detection.

The advantages of the construction and of the method of operation of the seal will 100 be readily apparent to those skilled in the art to which it appertains. While we have described the principle of operation of the seal, together with the structure which we now consider to be the best embodiment 105 thereof, we desire to have it understood that the structure shown is merely illustrative, and that such changes may be made when desired as are within the scope of the invention as claimed. 110

What is claimed is:—

1. A seal comprising a registering mechanism, means adapted to removably connect the seal to a lock element, and means adapted to be moved by the lock element during the 115 application of the seal thereto to effect the actuation of the registering mechanism.

2. A seal comprising a registering mechanism, a lock element engaging tongue, means carried by the tongue and connected to said mechanism and adapted to be actuated by said element on the application of the seal thereto, and means for removably connecting the seal to said element. 120

3. A seal comprising a registering mechanism, a lock element engaging tongue, an element carried by the tongue and connected to said mechanism and adapted to be moved by said lock element to actuate said mechanism on the application of the seal, and a 125 130

retaining element adapted to engage the lock element to removably connect the seal thereto.

4. A seal comprising a registering mechanism, a lock element engaging tongue, a bar 50 slideable on the tongue and connected to said mechanism, and adapted to be actuated by the lock element on the application of the seal, and a retaining element adapted to engage the lock element.

5. A seal comprising a registering mechanism, a lock element engaging tongue, a bar slideable on the tongue and connected to said mechanism, and a lock element engaging 55 latch carried by the tongue.

6. A seal comprising a registering mechanism, a lock element engaging tongue, a bar slideable on the tongue and connected to said mechanism and adapted to be actuated by the lock element on the application of the seal, a lock element engaging latch carried by the tongue, a trigger carried by the tongue and connected to the latch, and a lug carried by the bar for engagement with 20 the trigger when the seal is in applied position.

7. A seal comprising a registering mechanism, a lock element engaging tongue, a bar slideable on the tongue and connected to said 25 mechanism and adapted to be actuated by the lock element on the application of the seal, a latch connected to the tongue and adapted to engage the lock element, a trigger pivotally connected to the tongue and having a pivotal and slideable connection with 35 the latch, and a lug carried by the bar for engagement with the trigger when the seal is in applied position.

8. A seal comprising a registering mechanism, a lock element engaging tongue, a bar slideable on the tongue and connected to said 40 mechanism and adapted to be actuated by the lock element on the application of the seal, a lock element engaging latch, and 45 means adapted to prevent the casual disconnection between the latch and lock element.

9. A seal comprising a stationary shaft, numbered wheels loosely mounted on the shaft, disks each provided with a radial

notch and secured to the wheels and having 50 a diameter less than that of the wheels, spur pinions secured to the opposite sides of certain of said wheels, a second stationary shaft, pinions provided with alternately arranged narrow and wide teeth, the wide teeth contacting with the peripheries of the disks and the narrow teeth engaging the spur gears, and actuating means connected to one of said 55 wheels.

10. A seal comprising a stationary shaft, 60 numbered wheels loosely mounted on the shaft, disks each provided with a radial notch and secured to the wheels and having a diameter less than that of the wheels, spur pinions secured to the opposite sides of certain of said wheels, a second stationary shaft, pinions provided with alternately arranged narrow and wide teeth, the wide teeth contacting with the peripheries of the disks and the narrow teeth engaging the spur 65 gears, a ratchet disk secured to the other side of the remaining wheel, a pawl engaging said ratchet wheel, a disk provided with a lug and a pawl of which the latter engages said ratchet disk, a pivoted lever adapted 70 when moved in one direction to engage said lug, and means adapted to actuate said lever on the application of the seal.

11. A seal comprising a registering mechanism including a ratchet disk, a second disk 80 provided with a pawl engaging said ratchet disk, a pivoted lever for actuating said last named disk, a lock element engaging tongue, a bar slideable on the tongue and connected to said lever and adapted to be actuated by 85 the lock element on the application of the seal, and a retaining element for engagement with the lock element.

12. A seal comprising a registering mechanism, means adapted to removably connect 90 the seal to a lock element, and means for operating the registering mechanism and adapted to be operated during the application of the seal to the lock element.

In testimony whereof we affix our signatures.

EUGENE O. MAN.
CLAUDE C. McFATE.
